UNITED STATES PATENT OFFICE

JOHN CLAYTON BACKUS, OF SMETHPORT, PENNSYLVANIA

UMBRELLA LOCK

Application filed October 28, 1929. Serial No. 402,964.

53 This invention relates more particularly to that type of locks which are used for holding umbrellas, and similar articles, against unlawful removal.

55 The lock is of the so-called key retaining type; that is, the type in which the key is held in the lock when the lock is open and not in use, and in which the key is freed when the lock is closed or in use. The construction is such that the insertion of the umbrella or other article in the lock releases the key, and the insertion of the key opens the lock and releases the article.

58 The object of the invention, more particularly is to take care of umbrellas and other articles having handles of comparatively large diameter, such as the umbrellas in common use at the present time. Inasmuch as locks of this kind are usually arranged in racks, and the space available for each lock is limited, special arrangements must be made whereby the locks can be placed in restricted locations, and yet be able to accommodate articles having handles of considerable size. Generally speaking, therefore, the lock comprises locking means adapted to be projected beyond the casing to grasp the article, and be drawn into a casing as the article is locked. By this arrangement, a lock adapted to take care of articles having large handles can be used in a space no larger than that required by locks of earlier forms.

Referring to the accompanying drawings: 35 Fig. 1 is a perspective view of a group of locks as they are commonly arranged, one being shown with its jaws closed and the key removed, and others with their jaws open and the keys in place.

40 Fig. 2 is a view of the lock with the top plate removed, and with the jaws open, an umbrella (or similar article) being shown in dotted lines in the position it first assumes when about to be locked.

45 Fig. 3 is a similar view, but with only part

of the top plate removed, and with the umbrella (or other article) in the position which it assumes during the locking operation.

50 Fig. 4 is a view similar to the two preceding figures, but showing the lock closed, and illustrating the umbrella (or other article) in two other positions which it assumes during the locking operation.

55 Fig. 5 is a bottom view of the lock with the jaws opened, but showing them in dotted lines as closed.

Fig. 6 is a section, taken on line 6—6 Fig. 3.

60 Fig. 7 is a longitudinal section, taken on the line 7—7, Fig. 3, and showing part of a rack to which the locks may be secured.

Fig. 8 is a plan view of the bottom of the casing.

65 Fig. 9 is a top plan view of the inner section.

Fig. 10 is a horizontal section taken through the inner section and showing some of the features not shown in Fig. 9.

70 Fig. 11 is a plan view of the follow-up slide mounted on and carried by the inner section.

Fig. 12 is a view of the lock lever.

75 Fig. 13 is a plan view of the key retaining lever.

Fig. 14 is a view of the key retaining lever looking toward the left of Fig. 13.

80 Fig. 15 is a plan view of the locking pawl which cooperates with the follow-up plate, shown in Fig. 11.

Fig. 16 is a plan view of the anti-pick device.

85 Fig. 17 is a view of the anti-pick device looking to the left, as shown in Fig. 16.

Fig. 18 is a view of one side of the key.

Fig. 19 is a view of the reverse side of the key.

Fig. 20 is a detail view showing the lock lever of Fig. 12 and its operating spring.

90 Fig. 21 is a detail view of the lock lever of

Fig. 12, in engagement with the parts with which it cooperates.

The operating parts of the lock are arranged within a casing of any suitable material, but preferably of sheet metal of substantial thickness. It consists essentially of a lower or box part, comprising a bottom 10 having sides 11 and 12, and a top or cover 13. The side 11 is provided at its front 10 end with a ledge 14, and the side 12 with a similar ledge 15 (Figs. 3 and 4), for a purpose to be described.

Closing the end of the casing is a plate 17 (Fig. 7), which, in the form here shown, 15 is attached to and forms a part of the top plate 13. It serves to close the rear end of the box and protect the key mechanism. Both the bottom 10 and the cover 13 are cut away as at 18, so that the handle of the 20 umbrella 19 (shown in dotted lines in various figures) may rest therein. The top and bottom of the casing are secured together by any suitable means, as by slots 20 in the box and tongues 21 in the top, as is common 25 in lock construction; and by pins 22, or other suitable means. The top 13, where it joins the upright part 17 is provided with a slot 23 (Figs. 3 and 7) for the reception of a key as will be later described.

30 Within the casing is slidably mounted an inner section 25, which carries the engaging devices. Various engaging means may be used, but in the form here shown two jaws are employed. One of the jaws 26 is pivoted thereto at 27, and the other 28 is pivoted thereto at 29. This inner section comprises a top plate 30, a bottom plate 31, and a connecting part 32. These parts may be made in one piece or constructed of separate sheets 35 secured together in any suitable manner as by slots and tongues in the usual way. The bottom plate 31 is made of a width such that it will slide freely within the box 10, but at the same time be guided by the sides 11 and 12 thereof.

45 The inner section may occupy either of two positions. When the lock is not in use and the jaws are open, it occupies the projected position shown in the right hand side of Fig. 1, and in Figs. 2, 3 and 5, in which the jaws are open and extend beyond the casing; when the lock is in use and the jaws closed, it occupies the inner position, as shown in the left hand side of Fig. 1, and 50 in Fig. 4. A spring 33 (Fig. 7), having one end attached to the box 10 by means of a tongue 34 or other suitable means, and the other to a hook 35 formed on an extension 36 of the inner section, tends normally to 55 project the inside section with the jaws 26 and 28, to the position shown in Figs. 2, 3 and 5.

Jaw 26 has an extension 37, which cooperates with some fulcrum as the pin 22; and 60 the jaw 28 has a similar extension 38, which

cooperates with a similar fulcrum, as pin 22 on the other side of the box. Thus, when the lock is open and the inner section is projected by its spring 33, the extensions 37 and 38, strike their respective fulcrum pins 70 22, and cause the jaws to open, as shown in Figs. 1, 2, 3 and 5. Stop lugs 40 two on each jaw (Figs. 9 and 10), adapted to move in cut away portions 41 in the connecting plate 32, are so formed and proportioned 75 that when the jaws are open these lugs strike against the rear of the connecting plate 32, thus limiting the opening of the jaws.

When the inner section 25, and the jaws 80 26 and 28, stand projected by the spring 33, the rear ends 37 and 38 of the jaws rest against their fulcrums 22 so as to be held open thereby, while the stop lugs 40 rest in slots 41 against the rear of the connecting plate 32, and limit the extent to which the jaws may be opened. The jaws are thus held rigidly when in open position, and can only be moved as the inner section moves 85 into the casing.

The jaws 26 and 28 have each a cam 42 to the rear of their respective pivots 27 and 29. When the inner section 25, with the jaws 26 and 28, is forced into the casing, these cams 42 strike the respective ledges 14 90 and 15, and the jaws are cammed thereby to closed position; and when the jaws are in closed position, these cams 42 rest against the edges of the ledges 14 and 15, and are thus held rigidly in closed position. Thus, when the jaws are open, their rear ends 37 and 38 rest against the pins 22, and are thereby held in open position, while their stop lugs 40 rest against the back of the connecting plate 32 and prevent their being 95 opened farther than intended; and when the lock is closed, the cams 42 rest against the ledges 14 and 15 and the jaws are thus prevented from being opened; and they are retained in this position so long as the inner 100 section remains within the casing.

105 The inner section 25, with the attached jaws 26 and 28, is held in closed or locked position by an element termed herein the lock lever. This is shown detached in Fig. 12. It comprises a body portion mounted by pivots 46 in supports 47 attached to or made a part of the bottom 10 of the box. It is separated a little from the bottom 10, and is normally held elevated by a spring 48 110 having one end surrounding a tongue 49 on the bottom 10 and the other resting in a recess 50 of the lever. The lever has the rear end thereof reduced as at 51, and this reduced portion normally lies in the path of 115 the key, so as to be depressed thereby when the key is inserted. Extending from one side of the lever is a lateral extension 52 having a right angled front side 53.

120 The tongue 36 of the inner section 25 120

is provided with a projection 55 on its under side, and this projection cooperates with the extension 52 of the lock lever 45. When the inner section is within the box and the jaws 5 are closed, the front edge of the projection 55 on the tongue 36 lies behind the straight side 53 of the extension 52 of the lock lever 45, and as the spring 48 holds the lock lever 45 raised, the inside section is thus retained in 10 place and the jaws held closed.

The front end 51 of this lever 45 which lies in the path of the key and is depressed as the key is inserted, thereby moving the edge 53 of the extension 52 of the lever 45 15 away from behind the projection 55 on the tongue 36 of the inside section, thus releasing the inner section, whereupon it will be projected by the spring 33, and the jaws opened.

20 While the lock is open the key 62 holds the lever 45 in depressed position. In closing the lock the lug 82 on the top plate of the inner section strikes the cam 81 on the lever 70, causing hook 74 on this lever to 25 be drawn from the notch 67 of the key, thus releasing the key and permitting spring 48 to raise the lever 45 so that face 53 thereof will engage with lug or projection 55 on the tongue 36.

30 As the inner section is forced in to close the lock, one side of the tongue 36 passes under a projection 57 formed with or secured to the bottom 10, preventing the tongue 36 being lifted to release the lug 55 from 35 the face 53 of the extension of the lock lever 45.

The bottom 10 of the box has secured thereto at its rear end a plate 60, forming one side of the key channel. Secured there- 40 to by any suitable means is a guide plate 61. This plate projects up through the opening 23 of the cover and extends above the same to form a guide for the key. It carries combination devices, and guiding 45 lugs for the key.

The key 62 is provided on one side with grooves 63 forming, with lugs in the plate 61, varying combinations; and with slots 64, by which it is guided by other lugs in its 50 movements. These combination and guiding devices form no part of this invention and so are not shown in detail herein. The key 62 is also provided with cam edges 65 and 66 on the lower side thereof, and notches 55 67 and 68 on the sides thereof. Only cer- tain of these features function in this construction, the purpose of which will be de- scribed later.

Means are provided for retaining the key 60 in place when the lock is open. A lever 70 is used for this purpose. This lever is provided with a part 71 bent into U form to form a suitable pivotal bearing on the post 72. Another part 73, is provided with a hook 74. This hook extends through an

opening in the plate 60, and into the notch 67 of the key, so as to hold the key in place when the latter is in position in the lock. A spring 77 (Fig. 2), having one end secured to a hook 78 on the lever, and the other to a lug 79 on the box tends to draw the lever into position to lock the key. Ex- 70 tending at an angle to the arm 70 is another arm 80 having a cam face 81, which cooperates with a lug 82 carried by the in- 75 side frame, and by which the lever is with- drawn.

When the lock is closed, the key may be withdrawn, but when the lock is open the key is locked in place by the hook 74 of the lever 70. When the key is fully depressed, the notch 67 thereof registers with the hook 74, and when the inner section has moved out the spring 77 causes the hook to enter the notch, thus locking the key in place. It is held retained by this means so long as the lock remains open. When the lock is closed, the lug 82 on the inner section strikes the cam face 81 of the arm 80 and turns the lever 70 on its pivot 72, thus withdrawing the hook 74 from the notch 67. The lever 45 then raises the key as its edge 53 locks behind the lug 55 on the inner section and the key may be withdrawn.

To prevent the lock being readily picked or opened in an unauthorized manner when the same is closed and the key withdrawn, a so-called anti-pick device is used. This consists of a plate 85 slidably mounted on the plate 60. This plate 85 is provided with a hook shaped lug 86, which lies at right angles to the body of the plate, and with two extensions 87 and 88. The lug 86 is adapted to pass through an elongated slot in the plate 60 into the path of the cam face 66 of the key 62 and is held therein by the hook on the lug 86 which engages behind the plate 60. The extension 87 extends above and is guided by a tongue 89 on the plate 60 (Fig. 6) and the extension 88 is adapted to pass beneath the lock lever 45 when the key is withdrawn and the lever is raised by its spring 48. A spring 90, having one end attached to a tongue 91 on the plate 85 and the other secured to the tongue 89 on the plate 60, draws the plate 100 to the right (Fig. 6).

Insertion of the key causes the cam face 66 to engage the lug 86 and force the plate to the left (Fig. 6); but when the key is 110 withdrawn, the spring 90 draws the plate to the right and causes the extension 88 thereof to pass beneath the lock lever 45, thus rendering it impossible to depress the lock lever by the insertion of anything by 115 which the end of the lever might be de- pressed.

Mounted on the inside section is a follow- 120 up slide 95, which is intended to press against the handle of the umbrella (or 125

other article) when in position, and hold the same closely to the jaws 26 and 28, thus preventing the same from being withdrawn by unauthorized persons. Inasmuch as the handle of umbrellas differ much in size, this plate is slidably and adjustably mounted on the inside section. The front of this slide is concaved to conform more or less closely to the handle of the umbrella, and its front edge 96 is turned down, so as to present a substantial surface to the umbrella when projected, and to engage with the body of the inner section 25 to force the same inward during the locking operation.

Flanges 97, one on either side, extend down the sides of the inner section 25 so as to be guided thereby. The rear end 98 is narrowed somewhat, and a tongue 99 formed on or secured thereto extends through a slot 100 in the top plate 30 of the inner section. The tongue is provided with lateral extensions 101, which are adapted to pass through lateral enlargements 102 of the slot. A spring 103, having one end secured to the tongue 99 on the slide and the other to a tongue 104 on the inner casing, tends to move the plate toward the jaws so as to clamp the handle of the umbrella against the jaws and thus prevent its removal.

A locking pawl 105, pivotally mounted at 106 on the sliding section 25, is used to lock the follow-up slide 95 against backward movement. The slide has one edge serrated as at 107, and a tooth 108 on the pawl 95 cooperates therewith. A spring 111, having one end secured to the pawl at 110, and the other end to a lug 109 on the inner section tends to draw the tooth 108 of the pawl towards the serrations 107. Formed with or attached to the pawl 105 is a lug 112 which passes through an orifice 113 in the inner section, and keeps the movement of the pawl within fixed limits.

The pawl also carries an arm 114 by which it is operated. When the inner section moves out, the arm 114 engages the post 22 and is turned upon its pivot 106 against the tension of its spring 111, thereby withdrawing its tooth 108 from the serrations 107 of the follow-up plate. The plate is now free to move either in or out without restraint. When the inner section is forced into the casing, the pawl 105 moves therewith, and the arm 114 moves away from the post 22, and its spring 111 moves the tooth 108 into position to engage the serrations 107. The follow-up plate may now move out against the jaws or article held thereby, but it cannot move back, because the tooth 108 of the pawl 105 engages the serrations 107 and prevents its backward movement.

For the purpose of mounting the locks, as upon a rack, the top bar of which is shown at 120, Figs. 2, 3 and 7, the locks are pro-

vided with suitable fastening devices. Any suitable means may be employed, but in the form here shown, the plate 13 is provided with an orifice through which a bolt 121, surrounded by a sleeve 122, is passed. The hole in the lower plate 10 is smaller than that in the top, and permits the bolt to pass but not the sleeve. The bolt passes through the top of the rack 120, and is tightened by the nut 123. This causes the sleeve 122 to press upon the bottom plate 10 and clamp the lock to the rack. A second fastening device consisting of a tongue 124, struck from, or secured to the bottom of the casting, may be bent around the edge of the rack as shown in Fig. 7. But, as stated before, these fastening devices are merely illustrative, and any other suitable means may be employed.

Lugs 104 on the top of the lock are for the insertion of number plates thereon.

The beveled edge 65 and the notch 68 of the key 62 have no function in this construction.

Operation

90

Assuming the lock to be open and the parts in normal position, the sliding section stands projected, the jaws are open, and the key is locked in place by the hook 74 of the key lock lever 70. In using the lock, the umbrella (or other article) is passed between the jaws and moved against the follow-up slide 95. The umbrella is illustrated in this position in Fig. 2. Pressure on the umbrella causes the slide 95 to move back against the tension of its spring 103, which is not as strong as the spring 33 which projects the inner section; the follow-up slide is thus moved back until the flange 96 thereof contacts with the body of the inner section 25. The parts are shown in this position in Fig. 3. Continued pressure now forces back both the follow-up plate and the inner section, and as they move, the cams 42 on the jaws engage their respective ledges 14 and 15 of the casing, and are thereby closed. The parts are now in the position shown in Fig. 4 with the umbrella in the rear of the two positions here shown. As pressure upon the umbrella is released, the follow-up plate 95 moves forward under the tension of its spring 103, and forces the umbrella over to the front position as shown in Fig. 7, where the follow-up plate assumes the position shown in dotted lines in that figure. The tooth 108 of pawl 105 engages serrations 107 as soon as the inner section is pushed back by slide 95. Slide 95 is then free to move forward but not backward. The article is now locked in position.

As the inner section moves into the casing, the key lock lever 70 is withdrawn by the lug 82 on the inner section engaging the

115

120

125

130

cam 81 on the lever 70, thereby withdrawing the hook 74 of the lever from the notch 67 of the key, whereupon the lock lever 45 is raised by its spring 48 to the point where its edge 53 on the projection 52 rises behind the lug 55 carried by the sliding section, thereby locking the sliding section in position. The key may now be withdrawn.

To open the lock it is only necessary to 10 insert the key and press down thereon. The beveled edge 66 engages the lug 86 of the anti-pick device, forcing the same to the left so as to withdraw the extension 88 from beneath the lock lever 45. Continued depression 15 of the key then forces the lock lever 45 down to the point where its edge 53 moves from behind the lug 55 on the sliding section. The spring 33 will then force the inner section out of the casing. As it moves 20 out, the rear ends 37 and 38 of the jaws 26 and 28 will engage the pins 22 and move to open position, as shown in Figs. 2 and 3. At the same time, the key lock lever 70 will be released by the inner section, and the 25 hook 74 will engage the notch 67 of the key and prevent its removal.

Having thus described the invention, what is claimed as new is:

1. In a lock, the combination of a casing, 30 a section movable into and out of the casing, jaws pivoted to the movable section, means for opening the jaws as the movable section is moved out, and means for closing the jaws as the movable section moves in.

2. In a lock, the combination of a casing, 35 a section movable into and out of the casing, jaws pivoted to the movable section, means for opening the jaws as the movable section is moved out, means for limiting the extent 40 of opening of the jaws, and means for closing jaws as the movable section moves in.

3. In a lock, the combination of a casing, 45 a section movable into and out of the casing, jaws carried by the movable section, means for opening the jaws as the movable section is moved out, means for closing the jaws as the inner section is moved in, and means for limiting the outward movement 50 of the movable section.

4. In a lock, the combination of a casing, 55 a section movable with respect to the casing, locking means mounted upon the movable section, means for shifting the movable section with respect to the casing, means for operating the locking means to open the same when the movable section moves in one direction, and means for operating the locking means to close the same when the movable section moves in the opposite direction.

5. In a lock, the combination of a casing, 60 a section movable within the casing, locking means mounted upon the movable section, an extension on the rear of the locking means, stopping means in the path of the extension on the locking means, and means for

projecting the movable section thus bringing the extension of the locking means into co-operative relation with its stopping means thereby causing the engaging means to be opened by the movement of the movable 70 section.

6. In a lock, the combination of a casing, 75 a section movable within the casing, locking means pivoted upon the movable section, an extension on the locking means at one side of the pivot, a stop in the path of the extension, a cam on the locking means on the other side of the pivot, whereby the stop opens the locking means as the movable section is moved in one direction and the cam 80 closes the locking means as the movable section moves in the other direction.

7. In a lock, the combination of a casing, 85 a section movable within the casing, jaws pivoted upon the movable section, an extension on the rear of each jaw, means for limiting the opening movement of the jaws, a cam on each jaw, stops for engaging the rear extensions of the jaws when the movable section is moved out of the casing, and means for cooperating with the cams on the jaws to close the same when the movable section is moved into the casing.

8. In a lock, the combination of a casing, 95 an inner section movable into and out of the casing, jaws pivoted upon the inner section, an extension on the rear of each jaw, stops for engaging the rear extensions of the jaws for opening the same as the inner section moves out of the casing, stops on the jaws for 100 engaging the inner section to limit the opening of the jaws, a cam on each jaw for closing the jaws as the inner section is moved into the casing to close the lock.

9. In a lock, the combination of a casing 105 having an opening in one end thereof, stops one on either side of the opening, an inner section adapted to move in the opening, locking jaws pivoted on and carried by the inner section, extensions one on the rear of 110 each jaw adapted to coact with the stops in the casing, whereby as the inner section moves out the jaws are opened, and the outward movement of the inner section limited.

10. In a lock, the combination of a casing 115 having an opening in one end thereof, ledges one on either side of the outer section, locking jaws pivoted on and carried by the inner section, extensions one on the rear of each jaw adapted to cooperate with the stops to open the jaws and limit the outward movement of the inner section, cams one on each jaw adapted to cooperate with the ledges on the casing to close and hold closed the 120 jaws as the inner section moves into the 125 casing.

11. In a lock, the combination of an outer 130 casing, an inner section movable into and out of the casing, locking means carried by the inner section, and a follow-up plate

- movably secured to the inner section adapted to cooperate with the locking means carried by the inner section.
12. In a lock, the combination of a casing, a section movable into and out of the casing, jaws pivoted to the movable section, a follow-up plate mounted on the movable section and movable with respect to the jaws to grasp the article to be retained, means for moving the plate toward the jaws, and means for locking the plate against return movement when the inner section is within the casing.
13. In a lock, the combination of a casing, an inner section movable into and out of the casing, locking means carried by the inner section, a movable plate mounted on the inner section and adapted to cooperate with the locking means, means for locking the plate against movement in one direction when the inner section is within the casing, and means for disabling the last mentioned locking means when the inner section is out of the casing.
14. In a lock, the combination of a casing, a section movable with respect to the casing, locking means pivoted upon the movable section, key releasable means for holding the movable section with respect to the casing, means for projecting the movable section when the holding means is released, means for opening the locking means when the movable section is projected, and means for closing the locking means when the movable section moves into the casing.
15. In a lock, the combination of a casing, a section movable with respect to the casing, locking means pivoted upon the movable section, key releasable means for holding the movable section with respect to the casing, means for projecting the movable section when the holding means is released, means for opening and holding open the jaws when the movable section is projected, and means for closing and holding closed the jaws when the movable section moves into the casing.
16. In a lock, the combination of an outer casing, an inner section movable into and out of the casing, locking means carried by the inner section, a movable plate mounted on the inner section and adapted to cooperate with the locking means, means for moving the plate toward the locking means, means for locking the plate from movement away from the locking means, and means operated by the movement of the inner section for disabling the plate locking means when the inner section is in its outer position and enabling the same when the inner section is in its inner position.
17. In a lock, the combination of an outer casing, an inner section movable into and out of the casing, locking means carried by the inner section, key operated means for retaining the inner section within the casing, means for retaining the key in the lock when the inner section is out of the outer casing and the lock is open, and means for releasing the key retaining means when the inner section is within the outer casing and the lock closed.
18. In a lock, the combination of a casing, a section movable into and out of the casing, locking means carried by the inner section, a follow-up plate movably mounted on the inner section to cooperate with the locking means, means for moving the follow-up plate toward the locking means, means for preventing the return movement of the follow-up plate while the lock is closed, and means for disabling the last mentioned means when the lock is open.
19. In a lock, the combination of a casing, a section movable into and out of the casing, locking jaws pivoted upon the inner section, a follow-up plate movably mounted on the inner section, a spring for moving the follow-up plate toward the jaws, a pawl for engaging the plate to prevent its return when the lock is closed, and means for disabling the pawl when the lock is open.
20. In a lock, the combination of a casing, a section movable into and out of the casing, locking jaws pivoted upon the inner section and movable therewith, a follow-up plate provided with serrations movably mounted on the inner section, a pawl mounted on the inner section to engage the serrations and prevent return of the plate when the lock is closed, and means carried by the casing for disabling the pawl when the lock is open.
21. In a lock, the combination of an outer casing, an inner section movable into and out of the casing, locking means carried by the inner casing, key operated means for retaining the inner section within the casing, means for retaining the key in the lock when the inner section is out of the casing and the lock is open, and means operated by the movement of the inner section to close the lock for disabling the key retaining means.
22. In a lock, the combination of a casing, an inner section movable within the casing, locking means carried by the inner section, a key operated lever for retaining the inner section within the casing, an anti-pick device having one part thereof adapted to pass beneath and thus prevent operation of the key operated lever when the key is not in the lock and adapted to be disabled by the insertion of the key into the lock so that the lever may be operated.
23. In a lock, the combination of a casing, an inner section movable with respect to the casing, locking devices mounted on the inner section, a follow-up plate mounted for movement on the inner section, means whereby pressure applied to the follow-up

plate will first cause the same to move upon the inner section and thereafter cause the inner section to move therewith, means for retaining the inner section within the casting, means for projecting the follow-up plate when pressure thereon is released, and means for preventing return movement of the follow-up plate.

In testimony whereof I hereby affix my signature.

10 JOHN CLAYTON BACKUS.
